UNITED STATES PATENT OFFICE.

NANCY A. WESTBROOK, OF MASON, TEXAS, ASSIGNOR OF ONE-HALF TO
BENJAMIN F. GOOCH, OF MASON, TEXAS.

SPRING-CLAMP.

SPECIFICATION forming part of Letters Patent No. 717,729, dated January 6, 1903.

Application filed May 8, 1902. Serial No. 106,474. (No model.)

To all whom it may concern:

Be it known that I, NANCY A. WESTBROOK, a citizen of the United States, residing at Mason, in the county of Mason and State of Texas, 5 have invented a new and useful Spring-Clamp, of which the following is a specification.

This invention relates to devices for suspending small articles—such as towels, dish-cloths, and napkins—and which may also be 10 employed for hanging window-curtains, portières, goods in show-windows, and similar purposes; and the invention consists in the improved construction and arrangement of parts, which will be hereinafter shown and 15 described and then specifically pointed out in the claim.

In the drawings illustrative of the invention, Figure 1 is a perspective view of the device, and Fig. 2 is a similar view illustrating 20 a modification in the construction.

In this invention are comprised two bars 5 and 6, having opposing jaws 7 and 8 at one end, preferably with interlocking serrations 9, as shown in Fig. 2, and diverging at the 25 other ends and preferably extended into finger-grips or thumb-pieces 10 and 11, as shown. The two bars are shown united by a spring-rod 12 with a central eye 13, the force of the 30 spring being exerted to maintain the jaws 7 and 8 normally closed. Permanently engaging the eye 13 of the spring-rod 12 is a screw-eye 14, by which means the clamp may be secured in any required locality.

In Fig. 2 the screw-eye 14 is shown with its 35 ring portion large enough to permit the finger-grip ends of the clamp to pass through the eye, so that the clamp will hang vertically or in alinement with the screw-eye, which will be the form employed when the device 40 is suspended from a ceiling or from the lower sides of shelves or from the ceilings of wardrobes and closets and in similar localities, while the form shown in Fig. 1 will be preferable where the device is to be employed 45 upon vertical walls or in similar localities.

In Fig. 2 the opposing jaws are shown with interengaging teeth or serrations 9, which may be desirable under some circumstances to increase the "grip" of the jaws.

The serrated jaws may be required in holding some kinds of articles, but may not be required for others, and I do not wish to be limited to their use, as they may be employed or not, as required.

The form of clip herein shown may be altered and modified within the scope of my invention, provided that the main feature of the device, which consists of the spring member connecting the two clamping members and formed with an eye engaged by a permanently-attached screw-eye, is retained. In this feature, it will be observed, lies the improvement over present devices of this class, and I would have it specially noticed that by using a large screw-eye, as shown in Fig. 65 2, the device may be suspended in a vertical position and conveniently operated. This screw-eye, therefore, is an important and practically permanent part of the article.

What I claim is—

As a new article of manufacture, a clamp comprising two clamping members provided at opposite ends thereof with clamping-jaws and thumb-pieces, a spring permanently connecting said clamping members and having 75 a coil formed thereon, and a screw-eye permanently engaging said coil, said screw-eye being sufficiently large to admit the opposing thumb-pieces of the device when vertically disposed.

In testimony that I claim the foregoing as my own I have hereto affixed my signature in the presence of two witnesses.

NANCY A. WESTBROOK.
